[57] **CLAIM**

The ornamental design for the lopper, as shown and described.

DESCRIPTION

FIG. 1 is a right side perspective view of the lopper showing our new design;

FIG. 2 is an enlarged left plan view of the lopper of FIG. 1;

FIG. 3 is a top plan view of the lopper of FIG. 1;

FIG. 4 is a rear plan view of the lopper of FIG. 1;

FIG. 5 is a front plan view of the lopper of FIG. 1;

FIG. 6 is a bottom plan view of the lopper of FIG. 1; and,

FIG. 7 is a right plan view of the lopper of FIG. 1.

The broken line showing of lopper handles is for illustrative purposes only and forms no part of the claimed design.
